his ATTORNEY.

UNITED STATES PATENT OFFICE.

GUSTAV FELGER, OF NUEREMBERG, GERMANY.

DESIGN FOR A PENCIL.

Application filed August 24, 1927. Serial No. 23,191. Term of patent 3½ years.

To all whom it may concern:

Be it known that I, GUSTAV FELGER, a citizen of the Republic of Germany, residing at Nuremberg, Bavaria, Germany, have invented a new, original, and ornamental Design for Pencils, of which the following is a specification, reference being had to the accompanying drawing, forming part thereof.

The figure is a perspective view of a pencil showing my new design.

I claim:

The ornamental design for a pencil as shown.

In testimony whereof I affix my signature.

GUSTAV FELGER.
